UNITED STATES PATENT OFFICE

156,638

COMBINATION ICE AND SNOW SCRAPER

David A. Lifshutz and Leo H. Weiss,
Denver, Colo.

Application March 5, 1948, Serial No. 144,918

Term of patent 14 years

(Cl. D9—8)

To all whom it may concern:

Be it known that we, David A. Lifshutz and Leo H. Weiss, both citizens of the United States, residing in the city and county of Denver and State of Colorado, have invented a new, original, and ornamental Design for a Combination Ice and Snow Scraper, of which the following is a specification, reference being had to the accompanying drawing.

In the drawing:

Figure 1 is a top plan view of a combination ice and snow scraper, showing our new design;

Figure 2 is a side elevation thereof;

Figure 3 is a section taken on line 3—3, Figure 1; and

Figure 4 is a section taken on line 4—4, Figure 1.

We claim:

The ornamental design for a combination ice and snow scraper, as shown.

DAVID A. LIFSHUTZ.
LEO H. WEISS.
